CLAIM

The ornamental design for a charging pile as shown and described.

DESCRIPTION

FIG. 1 is a perspective view of a charging pile showing our new design.

FIG. 2 is a front view of a charging pile.

FIG. 3 is a rear view of a charging pile.

FIG. 4 is a left side view of a charging pile.

FIG. 5 is a right side view of a charging pile.

FIG. 6 is a top view of a charging pile.

FIG. 7 is a bottom view of a charging pile.

FIG. 8 is an enlarged detail view of area 8 shown in FIG. 2.

FIG. 9 is an enlarged detail view of area 9 shown in FIG. 2; and,

FIG. 10 is an enlarged detail view of area 10 shown in FIG. 2.

In FIGS. 1, 3, 4, 5, 6, and 7 the broken lines depict portions of the charging pile that form no part of the claimed design. In FIGS. 2, 8, 9, and 10 the broken lines are for the purpose of illustrating portions of the charging pile and boundary lines of the enlarged view that form no part of the claimed design.

The diagonal shade lines is a transparent surface.

1 Claim, 10 Drawing Sheets
